S. A. QUILLEN.
PRESERVING APPARATUS.
APPLICATION FILED OCT. 13, 1917.

Patented Apr. 9, 1918.

UNITED STATES PATENT OFFICE.

SARAH A. QUILLEN, OF GATE CITY, VIRGINIA.

PRESERVING APPARATUS.

1,262,094.

Specification of Letters Patent.

Patented Apr. 9, 1918.

Application filed October 13, 1917. Serial No. 196,549.

To all whom it may concern:

Be it known that I, SARAH A. QUILLEN, a citizen of the United States, residing at Gate City, in the county of Scott and State of Virginia, have invented certain new and useful Improvements in Preserving Apparatus, of which the following is a specification, reference being had to the accompanying drawings.

10 This invention relates to certain improvements in preserving apparatus and it is an object of the invention to provide a novel and improved device of this general character including a heat generating unit together with a drying chamber and wherein means are provided for conveying heat from the unit to the chamber in order to subject the contents of the chamber to a temperature sufficient to evaporate the moisture contained 20 therein.

It is also an object of the invention to provide a novel and improved device of this general character including a heat generating unit or stove together with a drying 25 chamber and wherein said unit and chamber are in predetermined spaced relation so that the one will afford no interference with the other.

The invention consists in the details of 30 construction and in the combination and arrangement of the several parts of my improved preserving apparatus wherein certain important advantages are attained and the device rendered simpler, less expensive 35 and otherwise more convenient and advantageous for use, as will be hereinafter more fully set forth.

The novel features of my invention will hereinafter be definitely claimed.

40 In order that my invention may be the better understood I will now proceed to describe the same with reference to the accompanying drawings wherein:

Figure 1 is a view partly in elevation and 45 partly in section illustrating an apparatus constructed in accordance with an embodiment of my invention; and

Fig. 2 is a fragmentary vertical sectional view taken through the upper portion of the 50 casing as disclosed in Fig. 1.

As disclosed in the accompanying drawings U denotes a heating unit or a stove of any preferred type but preferably a wood or coal burner and which is of such dimensions

as to be employed with convenience and facility in the boiling of vegetables, fruit or the like to be preserved. 55

Arranged at one side of the unit or stove U and sufficiently spaced therefrom so that the one will afford no obstruction to the other is a casing C affording a drying chamber B and the top of said chamber is provided with a draft opening 1 having disposed thereover a reticulated fabric 2 of predetermined mesh. Also co-acting with the opening 1 is a door 3 whereby the opening 1 may be entirely closed or partially opened in accordance with the requirements of practice. The front wall of the casing is provided with a plurality of openings 4 for the admission of the drying trays 5 which slide like drawers upon the supporting cleats 6. Each of the trays consists of a rectangular frame provided with a perforate bottom 7 formed preferably of wire mesh. 75

In communication with the interior of the unit or stove U are the pipes 9 which lead to the casing C and extend upwardly therethrough through the bottom thereof. The pipes 9 also extend through the top of the casing and have their upper or extended portions disposed laterally of the casing and terminating to one side thereof. Positioned within the heating unit U, herein disclosed as a conventional type of stove, and co-acting 85 with the entrance N of the pipes 9 is a swinging plate or damper 10 which serves to control the flow through said pipes so that the heat within the casing C may be readily and conveniently regulated. It will also be 90 understood that should the heat within the casing C reach an excessively high degree the door 3 may be opened to permit escape of the excessive heat.

The trays 5 are adapted to contain fruit, 95 vegetables or the like to be preserved by drying or evaporation. It will therefore be at once appreciated that with my improved apparatus an increased amount of work may be accomplished in view of the fact that at the time the heating unit or stove U is being employed for cooking purposes the heat generated by said unit or stove may be employed in the drying or evaporation of the fruit or the like arranged within the casing C. 100

It is preferred that the heating unit or stove U be provided with the shelf or table

11 to support jars or other containers into which the preserves or the like are adapted to be stored.

From the foregoing description, it is thought to be obvious that a preserving apparatus constructed in accordance with my invention is particularly well adapted for use by reason of the convenience and facility with which it may be assembled and 10 operated and it will also be obvious that my invention is susceptible of some change and modification without materially departing from the principles and spirit thereof and for this reason I do not wish to be understood as limiting myself to the precise arrangement and formation of the several parts herein shown in carrying out my invention in practice except as hereinafter claimed.

20 I claim:

1. A preserving apparatus comprising in combination, a heat generating unit, a drying chamber supported independently of the heating unit and heat conveying pipes lead-

ing from the heat generating unit and disposed upwardly through the drying chamber, said pipes extending through the bottom and top of the drying chamber, and terminating above the top of said chamber, the upper portions of said pipes being disposed laterally and terminating to one side of the chamber.

2. A preserving apparatus comprising in combination, a heat generating unit, a drying chamber supported independently of the heating unit and heat conveying pipes leading from the heat generating unit and disposed upwardly through the drying chamber, and a swinging plate supported within the heat generating unit and coacting with the entrance ends of the pipes for controlling the flow through the pipes.

In testimony whereof I hereunto affix my signature in the presence of two witnesses.

MRS. SARAH A. QUILLENN.

Witnesses:

J. U. CARTER,
W. I. PENDLETON.
